UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

WATER-COOLED FURNACE-DOOR FRAME.

1,191,519.

Specification of Letters Patent. Patented July 18, 1916.

Application filed December 1, 1915. Serial No. 64,453.

To all whom it may concern:

Be it known that I, LUTHER L. KNOX, a citizen of the United States, residing at Avalon, Allegheny county, Pennsylvania, have 5 invented a new and useful Water-Cooled Furnace-Door Frame, of which the following is a full, clear, and exact description, reference being had to the accompanying drawings, forming part of this specification, 10 in which—

Figure 1 is a front elevation, partly in section, of a door frame embodying my invention, and Figs. 2 and 3 are sections taken, respectively, on the lines II—II and III—

15 III of Fig. 1.

My invention has relation to water cooled door frame structures, and more particularly to hollow structures formed from sheet metal.

20 One object of my invention is to provide a structure of this general character made from sheet metal plate members united at their meeting portions by means of welded joints, and which joints are located so as to 25 be at a distance from the door opening through the structure.

A further object of my invention is to provide a structure of this character in 30 which the door opening is free from sharp corners. Such corners are objectionable in these structures, since, owing to the expansion and contraction strains, they are usually 35 the portions of the structure which give way soonest in use.

35 A still further object of my invention is to provide a structure of this kind which can be readily manufactured at a relatively low cost, and which will be strong and durable in service.

40 Referring to the accompanying drawings, in which I have illustrated the preferred embodiment of my invention, the door structure is formed from an outer plate member 2 and an inner plate member 3. The outer 45 plate member 2 has its upper edge portion bent inwardly to form the top wall 4 of the structure, the free edge of this flange being welded at 5 to the inner surface of the inner plate member 3, the latter being preferably 50 extended upwardly beyond the welding point 5, as indicated, to form a securing flange 6. The plate member 2 is cut away 55 to form the door opening 7 therethrough, this opening having the rounded corner portions

8. The lateral edge portions of the member 55 2 are shaped to form the offsets 9 which act as door guides.

The lateral edges of the inner plate member 3 are bent forwardly at substantially right angles to form the side walls 10 of the structure, their free edges being welded at 11 to the free lateral edges of the plate member 2. The plate member 3 is also cut away to form the door opening; and the edge portions of the metal around this opening are bent outwardly at substantially right angles to form the wall 12 of the opening; and the edges are then further reversely bent as shown at 13, the free edges of these bent portions being welded at 14 to the free 65 edges of the plate member 2 around said opening. It will be seen, therefore, that in forming the structure, the opening cut in the plate member 2 is larger than the finished opening, while that cut in the member 70 3 is considerably smaller than the finished opening. In this manner the weld at 14 is brought to the outer face of the structure and at a point removed from the opening, where it is not only protected from the 75 action of the most intense heat, but is also at a point where it will not be injured by contact with anything introduced through the door opening, such as a charging box or ram. The flanges 12 of the member 3 can 80 be shaped to conform to the rounded corners of the opening without any cutting or welding, thus making this wall continuous around the entire perimeter of the opening. At 85 the bottom of the structure the narrow connecting portion 15 of the plate member 2 is welded at one edge to the flange 13 of the plate member 3, and at its other edge is welded at 16 to the free edge of the bottom 90 forming flange 17 of the plate member 3. 95

My invention provides a hollow sheet metal door structure composed of two plate members which can be readily cut, die-shaped and welded. The location of the weld at points removed from the door opening, and also from the inner surface of the structure greatly increases its durability.

18 designates an inlet pipe for the cooling fluid, this pipe being shown as extending downwardly within one side of the structure to a point near the bottom thereof.

19 designates the outlet for the heated fluid at the opposite upper corner of the

structure. The inlet and outlet connections may be welded to the top wall of the structure.

20 designates suitable spacers which are placed between the two plate members and welded thereto.

I do not wish to limit myself to the exact construction which I have herein shown and described, since it will be obvious that many 10 modifications can be made in the details thereof without departing from the spirit and scope of my invention as defined in the appended claims.

I claim:

15 1. A hollow sheet metal door frame structure composed of inner and outer plate members, each of said members having a door opening formed therein, the metal surrounding the door opening in one of the 20 members being bent at substantially right angles to form the wall of the door opening and its free edge portion again bent in a direction away from said opening and substantially parallel to the plane of the door, 25 and welded to the edge of the other plate around said opening, substantially as described.

2. A hollow sheet metal door frame structure composed of inner and outer plate members, each of said members having a door opening formed therein, the metal surrounding the door opening in one of the 30 members being bent at substantially right angles to form the wall of the door opening and its free edge portion again bent in a direction away from said opening and substantially parallel to the plane of the door, 35 and welded to the edge of the other plate around said opening, the wall forming flange of said opening being continuous and rounded at the corners of the opening, substantially as described.

3. A hollow sheet metal door frame structure comprising inner and outer plates of 45 sheet metal, the outer plate having a portion thereof cut away to form a door opening therethrough, and the inner plate also having a cut away portion, with the metal adjacent to said portion bent outwardly at 50 substantially right angles to form the wall of said opening, and then again bent to meet the edge of the cut away portion of the other sheet to which it is welded, substantially as described.

55 4. A hollow sheet metal door frame structure comprising inner and outer plates of sheet metal, the outer plate having a portion thereof cut away to form a door opening therethrough, and the inner plate also

having a cut away portion, with the metal 60 adjacent to said portion bent outwardly at substantially right angles to form the wall of said opening, and then again bent to meet the edge of the cut away portion of the other sheet to which it is welded, the flange 65 forming wall of the inner sheet being continuous and rounded at the corners, substantially as described.

5. A hollow sheet metal door frame structure comprising inner and outer plates of 70 sheet metal, the outer plate having a portion thereof cut away to form a door opening therethrough, and the inner plate also having a cut away portion, with the metal 75 adjacent to said portion bent outwardly at substantially right angles to form the wall of said opening, and then again bent to meet the edge of the cut away portion of the other sheet to which it is welded, and the structure having a continuous water circulating 80 space entirely around said opening, substantially as described.

6. A hollow sheet metal door frame structure having a door opening therethrough and a bottom portion below said opening, 85 said bottom portion having its bottom wall formed by an outwardly turned flange of the inner plate member of the structure and having its top wall, which also forms the bottom wall of said opening, formed by 90 another outwardly turned flange portion of said inner plate member, substantially as described.

7. A hollow sheet-metal door-frame structure composed of inner and outer plate 95 members, each of said members having a door opening formed therein, the metal of one of said sheets being flanged to form the wall of the door opening, and its free edge portion being bent in a direction away from 100 said opening and welded to the other plate, substantially as described.

8. A hollow sheet-metal door-frame structure composed of inner and outer plate members, each of said members having a door 105 opening formed therein, the metal of one of said sheets being flanged to form the wall of the door opening, and its free edge portion being bent in a direction away from 110 said opening and welded to the other plate, said opening having rounded corner portions, substantially as described.

In testimony whereof, I have hereunto set my hand.

LUTHER L. KNOX.
